UNITED STATES PATENT OFFICE.

WILLIAM C. DEVEREAUX, OF DETROIT, MICHIGAN.

DESIGN FOR A DOME-LIGHT FRAME.

Application filed October 8, 1928. Serial No. 28,401. Term of patent 3½ years.

To all whom it may concern:

Be it known that I, WILLIAM C. DEVEREAUX, a citizen of the United States, residing in the city of Detroit, Wayne County, Michigan, have invented a new, original, and ornamental Design for Dome-Light Frame, of which the following is a specification, reference being had to the accompanying drawing, forming a part thereof.

Figure 1 is a front elevational view of a dome light frame, showing my new design.

Figure 2 is a side elevational view thereof.

I claim:

The ornamental design for a dome light frame as shown.

WILLIAM C. DEVEREAUX.
